UNITED STATES PATENT OFFICE.

DAVID G. SMYTH, OF HARTFORD, CONNECTICUT.

ELECTRIC PRINTING-MACHINE.

SPECIFICATION forming part of Letters Patent No. 760,813, dated May 24, 1904.

Application filed February 16, 1903. Serial No. 143,483. (No model.)

To all whom it may concern:

Be it known that I, DAVID G. SMYTH, a citizen of the United States, residing at Hartford, in the county of Hartford and State of Connecticut, have invented an Improvement in Electric Printing-Machines, of which the following is a specification.

My invention relates to electric printing-machines, and particularly to printing-telegraphs.

In carrying out my invention I employ a type-roll on which the characters are preferably arranged in spaced-apart rows of different lengths, and the type-roll is mounted on a shaft journaled in bearings on a suitable frame, and I also employ a striker adapted to bear upon the type to cause an imprint upon suitable material. Means are also provided for rotating the type-roll one or more spaces at a time, means for shifting the type-roll laterally one or more spaces at a time, means for maintaining the type-roll in any given position, means for actuating the striker, means actuated by the return of the striker for releasing the type-roll, and means for returning the type-roll to its initial position.

The apparatus may be operated locally or from a distant station, and the operation together with the detailed structure are herein-30 after more particularly set forth.

In the drawings, Figure 1 is a front elevation of the electric printing-machine, illustrating my invention. Fig. 2 is an end elevation and partial section on line $\alpha\alpha$, Fig. 1. Fig. 3 is a diagrammatic view of the type-roll. Fig. 4 is a diagrammatic view illustrating the means of short-circuiting the striker-magnet. Fig. 5 is a diagrammatic view of a local operating-circuit, and Fig. 6 is a diagrammatic view of the operating parts and circuits of a modified form of my invention.

a represents a base, to and upon which a frame a' and standards d d' are secured. Brackets 2 are supported by the frame a' , and 45 a type-roll shaft 3, carrying the type-roll b , is suitably journaled in the brackets 2. The type-roll shaft 3 is provided adjacent to the type-roll with a series of circumferential grooves 4 and also with the ratchets 5 and 7, 50 between which and insulated from the same

and the type-roll shaft is a metallic barrel 6. At one end of the type-roll shaft I may provide a spool 8 or other suitable means upon which a wire or string 10 may be wound, one end of the string being connected to a spring 11, by means of which parts the type-roll shaft is normally held in its revoluble initial position, and I also employ a spring 9, which may act against the spool 8 to normally maintain the type-roll shaft in its lateral initial 55 position. The characters employed in printing are preferably arranged on the surface of the type-roll in spaced-apart rows of different lengths, as indicated in Fig. 3, and the number of grooves 4 in the type-roll shaft preferably corresponds with the number of characters in the longest longitudinal row on the type-roll, and the number of teeth in the ratchet 5 preferably corresponds with the number of characters in the longest circumferential row on the type-roll. 60

I employ a striker b' , secured to an arm 12, pivoted at 13 in the frame a' and extending beyond its pivotal point and carrying an armature 14 of an electromagnet c , by which 75 the striker is operated. The opposite end of the striker-arm 12 carries a block 16, which is preferably of insulating material, and to the block 16 is pivotally connected a finger 17. The lower end of the finger 17 is provided with a projection by which, together with the spring 18 and stop 19, the finger is maintained in its proper position. To insure the perfect operation of the striker b' , I may employ a spring 15, extending between the 80 striker-arm 12 and the frame a' . A rocker-bar f extends between the standard d and the frame a' and is provided with a pawl 20, adapted to engage the grooves 4 in the type-roll shaft. To one end of the rocker-bar f a 85 rocker-arm 21 is secured, and the other end of the rocker-bar f is provided exteriorly of the frame with a rocker-arm 22. A pawl 23 is pivoted at 24 in the bracket 25 and is adapted to engage the teeth of the ratchet 7, 90 and the opposite end of the pawl 23 is extended beyond the frame a' in order to be engaged by the rocker-arm 22. Electromagnets e are also preferably supported by the frame a' , and the armature 26 of the electromagnets 100

e is preferably pivoted at 27 to a standard d' , supported by the base a . The free end of the armature 26 carries a pawl 28, adapted to engage the teeth of the ratchet 5, and a spring 29 may be employed to insure the proper operation of the pawl 28. A stop-screw 30, passing through an arm 31 of the standard d' , may be employed to adjust the movement of the armature 26, and a spring 32, extending 10 between the armature 26 and the arm 31, may be employed to normally hold the armature against the stop-screw 30. Electromagnets e' are supported by the standard d' , and their armature 33 is provided with an arm 35, the 15 end of which carries a pawl 36, adapted to engage the grooves 4 of the type-roll shaft. This arm 35, together with the armature 33, may be normally held away from the magnets e' by means of a spring 37, extending 20 from the said arm to the base a . The pawl 36 is held against an adjusting-screw 38 by a spring 39, as shown in Fig. 1, in such a position that the end of the pawl 36 just clears the grooved portion 4 on the type-wheel shaft when the arm 35 is in its normal position. 25

In the operation of the instrument locally an impulse or impulses may be sent through the electromagnets e by closing the circuit 30 through a switch h by causing the ends of the same to bear upon the contacts 39, (see Fig. 5,) it being apparent that for each impulse the armature will be attracted and cause the type-roll shaft and type-roll to move revolubly one space. After the type-roll shaft has thus been moved revolubly until the character to be used is in the line directly under the striker the shaft may be moved laterally to bring the said character immediately under 35 the striker by an impulse or impulses sent through the electromagnets e' by closing the circuit through the switch h and contacts 38, causing the armature to be attracted and the pawl 36 to engage one groove for each impulse and move the type-roll shaft and type-roll laterally the desired number of spaces corresponding to the number of impulses sent 40 through the magnet. The type-roll is now in the position for printing, and by sending 45 an impulse through the electromagnets e the pawl 28 is caused to contact with the barrel 6, which, together with the pawl 28, brush g , and frame of the apparatus, the striker-magnet e normally in a closed circuit, is short-circuited, permitting the striker b' to descend 50 and cause the imprint. It will be apparent that in the normal position the first circumferential row of characters cannot be directly under the striker, and the shaft must be 55 moved laterally at least one space every time an imprint is made, as otherwise the pawl 28 could not be made to contact with the barrel 6 to short-circuit the striker-magnet. Upon 60 the return of the pawl 28 the normal relations of the striker-magnets are resumed and

the striker returns to its original position. In the return movement of the striker a notch in the finger 17 engages the rocker-arm 21, causing the pawl 20 to be disengaged from a groove 4 and the rocker-arm 22 to bear upon 70 and cause the pawl 23 to be disengaged from the ratchet 7, thereby releasing the type-roll and its shaft, and when this relation maintains the spring 9 and cord 10 and spring 11 will cause the type-roll and its shaft to return 75 to its initial position in regard to both its lateral and revoluble movements, after which the apparatus is ready to print the next character.

To facilitate the speed with which the instrument may be operated, I may employ two sets of grooves 4, one being of double the number of the other, and a pair of ratchets 5, one having double the number of teeth of the other, in which instance it is also necessary 80 to employ a second set of electromagnets e^2 and e^4 , as shown diagrammatically in Fig. 6. It will be apparent that by employing the magnets e^2 and e^4 the type-roll may be moved either laterally or revolubly twice as far with one 85 impulse as could be done with one impulse sent through the magnets e or e' .

To operate the apparatus from a distant station, I prefer to employ a series of magnets m , m' , m^2 and m^3 and n , n' , n^2 , and n^3 . 90 The magnets m and m^2 , m' and m^3 , n and n^2 , and n' and n^3 are arranged with common yokes, m and m^2 having an armature 49, m' and m^3 an armature 50, n and n^2 an armature 51, and n' and n^3 an armature 52. The magnets 100 m and m' are on a local circuit which is normally closed, whereby the armatures 49 and 50 are normally held against the magnet-cores against the spring 53, and the magnets n and n' are also on a circuit normally closed, whereby 105 their armatures 51 and 52 are held against the magnet-cores against the spring 54. The circuit of magnets n and n' is preferably of twice the capacity of the circuit of the magnets m and m' . The magnets m^2 , m^3 , n^2 , and n^3 are in 110 circuit with the operating-switch, which may be employed locally or at a distant station. It will now be apparent that by closing the circuit through the contacts 40 by swinging the reversing-switch so as to bring its end to 115 bear upon said contacts the current, which I may call "positive," will be sent through the circuit 44, passing through the magnets n^3 , n^2 , m^3 , and m^2 , the magnets n and n' , being on a circuit of greater capacity than the one 120 transmitted through the operating-line, will not be affected. The magnet m^3 is so wound as to strengthen the magnet m' ; but the magnet m^2 is so wound as to neutralize the magnet m , whereby the armature 49 is released and 125 contact made at 45, closing the circuit through the electromagnet e , by which the type-roll is moved revolubly one space. To move the type-roll laterally one space at a time, the reversing-switch i is turned in the opposite di- 130

rection to close the circuit 44 through the contacts 41, in which instance a negative current is sent through the magnets m^2 and m^3 , the magnet m^2 strengthening the magnet m , 5 and the magnet m^3 neutralizing the magnet m' , releasing the armature 50, and closing the circuit to the magnets e^2 through the contacts 46.

In order to move the shaft revolubly two spaces at a time, the reversing-switch i' may 10 be moved to close the circuit 44 through the contacts 42, when the current, double the capacity previously employed, will be transmitted through the circuit through the magnets n^2 , n^3 , m^3 , and m^2 , which current will have no 15 influence on magnets m , m' , m^2 , and m^3 so far as the working of the apparatus is concerned, but will cause the magnet n^3 to strengthen the magnet n' and the magnet n^2 to neutralize the magnet n , releasing the armature 51 and closing 20 the circuit to the magnets e^2 through the contacts 47. The negative current in like manner may be transmitted through the line 44 by moving the reversing-switch i' to close the circuit through the contact 43, in which instance 25 the magnet n^3 is neutralized and the circuit to the magnets e^4 is closed through the contact 48 to obtain a lateral movement of two spaces in the type-roll shaft. By the arrangement of characters on the type-roll shaft 30 as shown in Fig. 3 I may employ fifty characters and any one of them may be employed with a maximum of six impulses—as, for instance, if it is desired to employ the character indicated at w it would be necessary to transmit four impulses through the magnet e^2 , one 35 through the magnet e , and one through the magnet e^4 , or if it is desired to employ the character indicated at w it would be necessary to send two impulses through the magnet e^2 , 40 one through the magnet e , and three through e^4 .

I do not limit myself to the precise operating apparatus shown and described, as any suitable apparatus may be employed as well as any suitable mechanism for feeding, shifting, 45 and regulating the paper and type-ribbon employed, these features forming no part of my present invention.

One end of the frame a' is provided with a bar 55, extending beyond the same to a distance 50 approximately equal to the maximum longitudinal travel of the type-roll shaft 3, and the type-roll shaft 3, adjacent to the end thereof, is provided with a pin 56, extending through the same and to an appreciable distance one 55 side thereof, so as to bear on one side of the rod 55 when the type-roll shaft is in one position and to bear on the opposite side of the rod 55 when the type-roll is in its extreme opposite position. The pin 56 limits the revoluble movement of the type-roll shaft 3 to a 60 movement slightly less than a complete revolution and acts as a stop to confine the revoluble movement of the type-roll shaft within these limits.

I claim as my invention—

1. In an electric printing-machine, the combination with a base and frame, of a shaft, a type-roll, a striker adapted to bear upon said type-roll, a battery, a magnet in local circuit therewith, a metallic barrel on and insulated from said shaft, a brush contacting with said barrel, a pawl adapted to contact with said barrel in predetermined positions, and electrical connections from said brush and pawl to the said battery-terminals, substantially as 75 set forth.

2. In an electric printing-machine, the combination with a base and frame, of a shaft, a type-roll, a striker adapted to bear upon the type-roll, a magnet normally energized by being in a local electric circuit, a metallic barrel on and insulated from said shaft, a brush contacting with said barrel, a pawl adapted to contact with said barrel, electrical connections from said pawl and brush to the magnet-battery and means for actuating the said pawl to cause the same to contact with said barrel and thereby short-circuit the magnet to allow the striker to operate, substantially as set forth. 85

3. In an electric printing-machine, the combination with a base and a frame, of a shaft, a metallic barrel on and insulated from said shaft, a type-roll, a ratchet, a magnet, an armature for the same, a pawl carried by said armature and normally adapted to engage said ratchet, and after the shaft has been moved longitudinally to contact with the said barrel when the said armature is actuated, means for energizing said magnet to move the shaft revolubly a predetermined number of spaces at 100 a time, a striker, means for actuating the same, means for maintaining the shaft in any of its revoluble positions, means for releasing the shaft simultaneously with the return of the striker, and means for returning the type-roll 105 to its initial position after each actuation of the striker, substantially as set forth.

4. In an electric printing-machine, the combination with a base and a frame, of a shaft with grooves therein, a magnet, an armature for the same, a pawl carried by said armature and adapted to engage said grooves, means for energizing said magnet to move the shaft laterally a predetermined number of spaces at 110 a time, a striker, means for actuating the same, a metallic barrel on and insulated from said shaft, a brush contacting with said barrel, a pawl adapted to contact with said barrel after the same has been shifted laterally, a battery and electrical connections from the said 115 brush and pawl to said battery, and means in the circuit of said battery for operating the said striker.

5. In an electric printing-machine, the combination with a shaft, a type-roll thereon, means for moving the type-roll revolubly a predetermined number of spaces at a time, and means for moving the type-roll laterally, 125

a predetermined number of spaces at a time, of a striker, means for actuating the same, a rocker-bar, a pawl on said rocker-bar and adapted to engage said type-roll shaft, a rocker-arm on one end of said rocker-bar, a ratchet on said type-roll shaft, a second pawl engaging the said ratchet and adapted to be actuated by the said rocker-arm, means actuated by the movement of the said striker to turn 10 the rocker-bar, disengaging the first aforesaid pawl causing the said rocker-arm to raise the said second pawl, disengaging the said ratchet, thereby releasing the type-roll shaft both revolubly and laterally, and means for 15 returning the shaft to its initial position after each actuation of the striker, substantially as set forth.

6. In an electric printing-machine, the combination with a shaft, a type-roll thereon, 20 means for moving the type-roll revolubly a predetermined number of spaces at a time, and means for moving the type-roll laterally a predetermined number of spaces at a time, of a striker, means for actuating the same, a 25 rocker-bar, a pawl on said rocker-bar and adapted to engage said type-roll shaft, a rocker-arm on one end of said rocker-bar, a ratchet on said type-roll shaft, a second pawl engaging the ratchet and adapted to be actuated by 30 the said rocker-arm, a second rocker-arm on the opposite end of the rocker-bar, a finger actuated by the said striker and adapted to contact with the last aforesaid rocker-arm to actuate the rocker-bar to operate the said 35

parts connected therewith to release the type- 35 roll shaft, and means for returning the type-roll shaft to its initial position after each actuation of the striker, substantially as set forth.

7. In an electric printing-machine, the combination with a shaft, a type-roll thereon, 40 means for moving the type-roll revolubly a predetermined number of spaces at a time and means for moving the type-roll laterally a predetermined number of spaces at a time, 45 of a striker, means for actuating the same, a rocker-bar, a pawl on said rocker-bar and adapted to engage said type-roll shaft, a rocker-arm on one end of said rocker-bar, a ratchet on said type-roll shaft, a second pawl 50 engaging the said ratchet and adapted to be actuated by the said rocker-arm, a second rocker-arm on the opposite end of the rocker-bar, a finger actuated by the said striker and adapted to contact with the last aforesaid 55 rocker-arm to actuate the rocker-bar to operate the said parts connected therewith to release the type-roll shaft, a spring, a spool, a string, and helical spring for returning the type-roll shaft to its initial position after each 60 actuation of the striker, substantially as set forth.

Signed by me this 29th day of January, 1903.
